UNITED STATES PATENT OFFICE.

CHARLES H. WILLCOX, OF NEW YORK, N. Y., ASSIGNOR TO THE WILLCOX & GIBBS SEWING MACHINE COMPANY, OF SAME PLACE.

SEWING-MACHINE NEEDLE.

SPECIFICATION forming part of Letters Patent No. 357,805, dated February 15, 1887.

Application filed June 8, 1886. Serial No. 204,649. (No model.)

To all whom it may concern:

Be it known that I, CHARLES H. WILLCOX, of New York city, in the county and State of New York, have invented a new and useful Improvement in Sewing-Machine Needles, which improvement is fully set forth in the following specification.

This invention relates to eye-pointed needles for use in sewing-machines, and particularly in sewing-machines which use an eye-pointed needle in connection with a hook-needle, as described in Wiseman's patents, No. 228,711, dated June 8, 1880, and No. 243,023, dated June 14, 1881, and in the application of myself and George H. Noble, filed June 8, 1886, and officially numbered 204,546. In machines of this latter class the two needles are set parallel, the hook-needle directly in front of the other, and are reciprocated together. The eye-pointed needle pushes the loop of sewing-thread through the fabric. The loop is then caught by looping mechanism, which places it in the hook-needle. This latter carries the loop through to the other side of the fabric. The eye-pointed needle, in again entering the fabric, passes through the loop, which drops off the hook-needle and is drawn against the eye-pointed needle, and when the latter is withdrawn for another stitch the thread locks the loop. When in these machines the looping mechanism takes the loop of thread from the eye-pointed needle, the thread is carried off at right angles to the axis of the eye, and a considerable length is drawn through the eye and rather sharply around the edge thereof, in order that the loop may be placed in the hook of the hook-needle. With the ordinary sewing-machine needle, which has a short groove on that side, the thread is apt to be frayed or cut.

To produce an efficient needle not open to this objection is mainly the object of the present invention, which to that end consists in an eye-pointed sewing-machine needle provided, in place of the ordinary short groove, with a flat surface formed by cutting away the cylindrical blade of the needle at and for a short distance above and below the eye, and having the edge where the eye joins said surface rounded, so that the thread can be drawn smoothly over and around the edge with but little or no liability to be worn or cut thereby.

In the accompanying drawings, which form a part of this specification, a needle constructed in accordance with the invention is shown on an enlarged scale, Figure I being an elevation looking at what would ordinarily be the short-groove side; Fig. II, a central longitudinal section through the axis of the needle and needle-eye, and Fig. III a cross-section on line III, looking in the direction of the arrow. The needle, as usual, consists of a shank, *a*, blade *b*, point *c*, and eye *d*. On the side shown in Fig. I, where the short groove ordinarily would be, the blade is cut away or ground off at and for a short distance above and below the eye *d*, leaving a flat surface, 300. This cutting or grinding is best done by the periphery of a cylindrical tool of comparatively large diameter, whose axis is at right angles to that of the needle. The object is to have practically a plane or flat surface where the eye terminates on that side of the needle, and to have this surface merge gradually into the regular cylindrical surface of the blade. The edge of the eye is rounded or counterbored, as shown at 301, so that the thread will run smoothly over it. Just below the eye there is a transverse notch or recess, 302, which is cut well in toward the axis of the needle, nearer than the flat surface at which the eye terminates.

On the side of the needle not shown in Fig. I is the usual long groove, which, however, is not made of uniform depth, as customary, but is shallower in proximity to the needle-eye, as shown at 303 in Fig. II, than it is nearer the shank, so as at that point to stiffen and strengthen the blade and compensate for the metal removed to form the notch 302.

The notch 302 permits the looper to work closer to the axis of the needle than it otherwise could. Were it not for this notch the surface 300 would or might extend below the eye precisely as it does extend above it; but, as shown, the notch cuts into the surface, leaving only a small space between the notch and the eye.

The shank *a* is flattened on one side for enabling it to be secured in the needle-carrier or needle-bar more accurately and firmly; but this flattening is no part of the invention.

Modifications may be made in details with-

out departing from the spirit of the invention, and parts of the invention may be used separately, as by omitting, for example, the transverse notch from the needle and providing it 5 with a long groove of uniform depth.

I claim—

1. An eye-pointed sewing-machine needle having the blade at and for a short distance above and below the eye on one side of said 10 blade cut away, leaving a flat surface where the eye terminates, and being provided with a long groove on the opposite side of said blade the edge where the eye joins said flat surface being rounded, substantially as de- 15 scribed.

2. An eye-pointed sewing-machine needle having on one side of the blade a flat surface where the eye terminates and a transverse notch below the eye, and on the opposite side of the blade a long groove, substantially as 20 described.

In testimony whereof I have signed this specification in the presence of two subscribing witnesses.

CHAS. H. WILLCOX.
